United States Patent Office.

JAMES F. WINCHELL, OF SPRINGFIELD, OHIO, ASSIGNOR TO HIMSELF
AND GEORGE C. STEELE.

Letters Patent No. 60,977, dated January 1, 1867.

IMPROVEMENT IN CORN HUSKER.

The Schedule referred to in these Letters Patent and making part of the same.

TO ALL WHOM IT MAY CONCERN:

Be it known that I, JAMES F. WINCHELL, of Springfield, in the county of Clark, and State of Ohio, have invented certain new and useful Improvements in Corn Huskers; and I do hereby declare that the following is a full, clear, and exact description thereof, reference being had to the accompanying drawings, making part of this specification, and to the letters of reference marked thereon, like letters indicating like parts wherever they occur.

Figure 1 is a plan view of the device, with its strap opened out.

Figure 2 is a side view of the same.

Figure 3 is a perspective view of it, as arranged for use.

My invention relates to that class of devices intended to be attached to the fingers of the operator, in husking corn, and consists in the special construction of the metallic portion, and so connecting it to the strap as to prevent the metal from coming in contact with the hand; and also in making the same adjustable in size, to suit different-sized hands. Various devices have heretofore been invented for this purpose, but usually they consist of a single piece of metal, bent so as to clasp the hand or the fingers, to hold it in place. These devices, when used, are apt to soon chafe the hand or fingers, and render them sore, thus preventing their use. Another kind consists of a piece of leather made to encircle the hand, and having a blade attached thereto, with its point resting in the palm of the hand, and pointing forward. This device, while avoiding the injury to the hand produced by the metal huskers referred to, is not convenient for use, on account of the blade being located in the palm of the hand; and neither this nor the former style is so constructed that they can be conveniently adjusted to different-sized hands. My invention has for its object the remedying of these difficulties, or, rather, the obviating of them, by a different construction of the device.

In the drawings, A represents a piece of metal, which may be cut out with a die or punch in the form represented in fig. 1. The point *a* is then curved, as shown in fig. 2, to form a hook with which to pierce and grasp the husks at the point of the ear of corn. Its rear end is also bent over to form a hook, *c*, as shown. I then provide a leather strap, as represented by B, and attach the plate A to it by means of one or more rivets, as shown in fig. 1, care being taken to have the under head of the rivet *b* flat and smooth, so as not to injure the hand. If desired, another piece of leather may be used to line the strap B, so as to cover the rivets, and thus render it still more perfect in this respect; though, if proper care be had in making it, this will not be necessary. I then cut a series of holes, as represented at *a*, fig. 1, of proper size to fasten that end of the strap B to the hook *c*, when the strap is bent around, as shown in fig. 3. By these means the instrument may be adjusted in size to fit the hand of any person, and thus the same instrument may be used by men or boys, as desired, thereby preventing the necessity of having a husker for each separate person.

In using it, it is designed to clasp around the last three fingers of the hand, thus leaving the first free, and giving greater freedom to the hand.

Having thus described my invention, what I claim, is—

The corn husker, consisting of the metal plate A, and the strap B, made adjustable in size, when constructed and arranged as herein shown and described.

JAMES F. WINCHELL.
